(57) **CLAIM**

The ornamental design for a helicopter fuselage frame, as shown and described.

DESCRIPTION

FIG. 1 is a first perspective view of an embodiment of a helicopter fuselage frame.

FIG. 2 is a second perspective view of an embodiment of a helicopter fuselage frame.

FIG. 3 is a top plan view of an embodiment of a helicopter fuselage frame.

FIG. 4 is a bottom plan view of an embodiment of a helicopter fuselage frame.

FIG. 5 is a front elevational view of an embodiment of a helicopter fuselage frame.

FIG. 6 is a rear elevational view of an embodiment of a helicopter fuselage frame.

FIG. 7 is a right side elevational view of an embodiment of a helicopter fuselage frame; and,

FIG. 8 is a left side elevational view of an embodiment of a helicopter fuselage frame.
